MEANS AND METHOD FOR SEPARATING
LINT FIBERS FROM COTTON SEEDS AND
CLEANING LINT FIBERS BY AIR WASHING

Pressley Earl Hopper, Dallas, Tex.

Application October 13, 1941, Serial No. 414,826

5 Claims. (Cl. 19—62)

This invention has reference to the ginning of cotton, but it relates more particularly to a means and method for separating lint fibers from cotton seed and cleaning motes, trash and other extraneous matter from the fibers in the ginning method in a conventional gin and linter gin.

One of the chief obstacles to the growers of cotton in realizing full benefits from the production of longer staple cotton is the fact that removal of trash from the longer staple varieties is more difficult and, where excessive amount of cleaning machinery is employed in the effort to pre-clean this cotton, the fibers are twisted into small threads between the seeds. Both the trash carried in the sample and the roping or twisting greatly reduce the value, therefore the method of air-washing the sample and thus eliminating the machining of the sample is most desirable in the ginning process.

This same thing applies on shorter varieties and more especially in the areas where cotton is "snapped" and separation made at the gins instead of hand picking. Many plants are unable to effect a thorough cleaning before the cotton is fed into the seed rolls and this method of cleaning the trash from the sample in the ginning process will be most valuable on all varieties of cotton where this method of gathering is employed.

A survey of results in the snap cotton areas reveals that the better staple varieties usually run so low in grade because of inability to remove the trash in the preparation that many times the shorter staple cotton actually gives greater returns to the grower in spite of the premiums for better staple cotton of equal grade.

In the conventional gin, the only means provided for the removal of trash is by centrifugal force or speed of the saws on air-blast gins and the same action by the saws and brush where brushes are used instead of the air-nozzle. Neither of these is positive because much of the extraneous matter is so nearly the same weight as the fibers that it cannot be dislodged in this manner. With the method of air-washing, the trash cannot escape removal because of its light weight.

Where cotton carries a relatively high moisture content it is next to impossible to remove the pin and leaf trash by conventional cleaning methods or moting; and, since this condition is more prevalent in the delta and other areas where the better staples are produced, it is very desirable to have a positive means of trash removal in spite of the moisture content, and also to have means

of reducing moisture content of the finished fibers.

In accordance with the preceding, it is therefore one of the objects of this invention to provide a cotton gin rib construction having a step-off or off-set on the upper surface of the rib or ribs adjacent the point where the gin-saw teeth pass between the ribs and out of the roll box.

Another object of the invention is the provision of a gin rib construction having a duct or channel or a plurality of ducts or channels therein, whereby air may be injected either through or between the gin ribs against the gin saw teeth or contiguous thereto and in a direction opposite the rotation of the gin saw teeth, in the removal of trash from the cotton fibers and preventing its passage from the roll box.

A further object of the invention is the provision of such a gin rib construction whereby an air stream or streams is or are directed against and/or contiguous to the gin saw teeth in a direction the reverse of the travel of the gin saws, whereby any cotton fibers not securely held by the gin saw teeth will be dislodged by said air stream or streams held within the seed roll. The advantages attained are elimination of loss of fiber and better and cleaner cotton sample as the fibers are thereby straightened and combed by the air current.

Another advantage attained by this invention is that of preventing cotton seed in the gin roll from being pulled into the crotches or spacing between the gin ribs by the saw teeth and attached fibers by keeping the cotton seed suspended above the top surface of the ribs in the area where the gin saw teeth pass between the gin ribs and out of the roll box.

Another advantage accomplished by the present invention is that of directing a high velocity stream or streams of heated air through the gin ribs in the removal of trash, as previously outlined, and to remove moisture from the lint fibers before they are taken from the seed roll and to so apply heat directly to the gin saw teeth in order that the fibers may be more readily and easily removed by the brush or air nozzle.

The drawings accompanying this specification illustrate a means whereby the above objects and advantages may be carried out, and in the said drawings:

Figure 1 is a fragmentary view in elevation of a gin rib constructed in accordance with this invention, and illustrating in section part of the gin rib, gin rib breast, air inlet duct, gin saw with dotted indication of the roll box;

Figure 2 is a sectional detail view on line 2-2 of the gin rib construction shown in Figure 3, the latter figure illustrating a modification of the gin rib and breast formation, and being taken on the line 3-3 of Figure 4;

Figure 4 is a detail fragmentary view of the front edge of one of the gin ribs;

Figure 5 is a detail view in fragmentary side elevation of a gin saw and gin rib showing the effect of the air stream in dislodging trash and the like from the cotton lint carried on the gin saw;

Figure 6 is a fragmentary side elevational view partly in section of another variation of the gin rib;

Figure 7 is a view similar to that of Figure 1, but illustrating a further modification of the gin rib with respect to the application thereto of an air nozzle;

Figure 8 is a rear edge view in part of Figure 7; and

Figure 9 is a perspective view of another modification of a gin rib, partly broken away.

In accordance with the drawings, in Figure 1 is shown a gin rib 1 with an off-set portion 2, the ribs being assembled in customary spaced relation with a battery of gin saws 3 and a roll box indicated by broken lines at 4. The upper end or ends 5 of the ribs are connected as shown to a gin breast element 6, the latter being bored at 7 for the passage of an air stream conducted from a suitable source through the pipe 8 in the direction of the arrows. In this form of rib construction the rib is channeled or bored to provide a passage indicated at 9 which is in line with the inlet or bore 7 and the passage 9 has two tributaries or ducts 10. It will be noted that the gin breast or element 6 has a slight rearward inclination in order that the air stream upon striking the off-set or step-off 2 will be directed in the direction of the plurality of arrows along or contiguous to the saw teeth and as indicated in Figure 5 the trash or extraneous matter A will be thrown back into the roll box 4 with the seed and prevented from passage between the ribs, and the lint indicated at L held on the saw teeth will be allowed to pass. The off-set tends to keep the cotton seed suspended above the top surface of the ribs while the fiber under the action of the high velocity air streams in the passage 7 and the bore 9 and ducts 10 and held on the saws is subjected to a thorough cleaning and straightening of the fibers in the case of long staple cotton.

Figure 3 shows a variation of the gin rib and the breast or element 6 to which the ribs are attached. In this variation the breast provides a chamber C, an air inlet 11, an air outlet 12, the chamber being common to all the ribs. The air passes through the bore 9 and is then made to pass out in two streams through the ducts 10, as in the former instance. The breast element 6 has a forward tilt and the bore 9 more downwardly inclined and curved slightly at 9-a.

In Figure 6 is shown another variation of the gin rib construction, the breast 6 being further inclined forwardly, the air entering at 13 and passing through the bore 9-a which as will be noted is almost perpendicular or vertical, and the rib is curved outwardly as at 15, whereby the air stream will be directed more upwardly. In Figure 7 the breast element 6 is tilted slightly rearwardly and the rib in this form is applicable to nozzle application, the air entering through and by means of the nozzle 16 and into the bore 9-b which is

brought almost directly vertical at its output end or termination and the air is directed in the direction of the arrows there shown. From Figure 8 (an edge view taken from the rear of Figure 7) it will be seen that the bore 9-b has a divisional partition 9-e whereby the air stream is split in two tributaries, thus subjecting the saw teeth to the action of the air along the entire length of the bore or bores of the tributaries 9-b. In Figure 7 the double passage or bore formation projects rearwardly from the upper end of the rib form where it is attached to the breast; but in Figure 9 the double passage formation 9-b is in line with the rear surface of the part 1-a of the rib.

From the foregoing it will be apparent that the disclosure presents a novel means and method for cleaning and otherwise improving the cotton sample and aid in the ginning of the cotton by the use of high velocity air currents in the regular ginning method rather than by endeavoring to eliminate trash and extraneous matter by moting methods. The present method and means here disclosed differs from all methods now being used in the cleaning of trash from the lint fiber in that it does not embody any change in the regular method of feeding cotton into the seed roll box or of controlling the discharge of the finished seed. It further differs from all moting methods in that by this means any fibers not securely held by the ginning saw teeth will be dislodged by the air stream and held within the seed roll box, being recovered by the ginning saw teeth, thereby eliminating any loss of fiber in the moting method.

It is believed that the foregoing explanation will be sufficient to enable any one to understand the operation of the invention without further discussion. It is to be understood, also, that the disclosure does not limit the invention to the precise means herein shown as various types of ducts and nozzles may be employed. The disclosure of the several types of rib construction air ducts and nozzles may be varied to any extent in keeping with the principle of the invention and which will be within the scope and range of the following claims.

What is claimed is:

1. In a cotton gin including a roll box, a gin rib construction comprising in combination with a plurality of gin saws, a plurality of gin ribs, a rail to which the gin ribs are secured, said rail having a passage for air under pressure, the upper portions of the gin ribs having one or more passages in open communication with the passage in said rail and terminating into ducts opening into the roll box adjacent to and between the gin saws, and means for supplying air under pressure through said passages or ducts into the roll box and against the saws in a direction opposite to the rotation of the gin saws thereby removing trash from the cotton on the saws.

2. A gin rib construction as claimed in claim 1, wherein the terminating ducts of the gin rib passages have openings in angular relation to the passages in the ribs, whereby the air is directed outwardly and upwardly, contiguous to and in a direction opposite to the rotation of the gin saws and removing trash and extraneous matter from the cotton lint collected by the gin saw teeth.

3. In a cotton gin including a roll box, a gin rib and rail construction, in combination with a plurality of gin saws, said rib having a head portion formed on its upper end, a passage in the head portion, said passage being directed angu-

larly downwardly into spaced ducts, each duct having an angular side opening outwardly of the ribs entering the roll box, said rail having an opening communicating with said rib passage, and means for passing air under pressure from an outside source through said passages and ducts into said roll box and against said saws in a direction opposite the rotation of the gin saws, to maintain the cotton seed in a suspended position above the ribs and removing trash from the cotton lint caught on the gin saw teeth.

4. In a cotton gin including a roll box, an upper rib rail, a plurality of gin ribs connected to said rail, and a plurality of rotary gin saws adapted to convey lint between said ribs; means for directing fluid under pressure against the saws in a direction opposite their direction of rota-

tion at points adjacent the points where the gin saw teeth pass between the ribs; but before passing out of the roll box, whereby trash and other extraneous material are removed from the lint without removal of the lint from the saws.

5. A method of freeing lint fibers from extraneous matter as the lint is carried upon rotary gin saws operating between stationary gin ribs in passing from the roll box, which comprises blowing fluid under pressure against the lint at approximately the point where the saw teeth pass between the gin ribs but before passing out of the roll box, and in a direction opposite to the direction of rotation of the gin saws.

PRESSLEY EARL HOPPER.
